UNITED STATES PATENT OFFICE.

WILLIAM H. BURK, OF CHICAGO, ILLINOIS, ASSIGNOR TO AMERICAN STEEL WINDOW COMPANY, OF CHICAGO, ILLINOIS, A CORPORATION OF ILLINOIS.

FASTENING DEVICE.

1,301,813.

Specification of Letters Patent. Patented Apr. 29, 1919.

Application filed February 25, 1918. Serial No 219,099.

To all whom it may concern:

Be it known that I, WILLIAM H. BURK, a citizen of the United States, residing at Chicago, county of Cook, and State of Illinois, have invented new and useful Improvements 5 in Fastening Devices, of which the following is a specification.

My invention relates to a fastening device intended more particularly for securing 10 in place the sashes of glazed steel partitions now in extensive use in large manufacturing and mercantile buildings in such manner that the sashes may be removed and replaced in taking down and reerecting the partitions 15 without breaking the putty or in any manner disturbing the glazing. The object of my invention is the provision of a fastener capable of such use, and which shall be convenient, sightly, and well adapted for the 20 purposes for which it was designed. My invention consists in the construction of such a device with and its application to a glazed sash and its supporting partition, and in the construction, formation and arrangement 25 of the device itself, as illustrated in the accompanying drawing and hereinafter described, the essential elements of my invention being more particularly pointed out in the appended claims.

30 Of the drawings Figure 1 shows a front view of part of a glazed partition to which my invention is applied; Fig. 2 is an enlarged horizontal section through a pair of fasteners and adjacent parts of two glazed 35 sashes and an interposed mullion of the partition structure as indicated by the line 2—2 of Fig. 1; Fig. 3 is a perspective view of a fastener member applied to a fragment of a sash, part of the putty being broken away; 40 Fig. 4 is a horizontal section corresponding to Fig. 2 but showing a modified form of fastener; and Fig. 5 is a horizontal section of a different modification, taken centrally of the block.

45 In a typical partition of the class for which my invention is particularly designed, the partition units (which individually may be made up wholly of glazed sash members, or may include swinging or sliding doors) 50 are adapted to be framed between vertical mullions 1, suitably secured at their bottom and suitably secured to the ceiling at their top, or connected by an impost member to form a secure partition frame. Usually the 55 lower portion of the partition consists of

sections known as "kick plates" (indicated by the reference numeral 2) secured between the mullions, above which are arranged the glass sash members or partition units to which my invention particularly 60 relates.

Describing now the particular structure and embodiment of my invention illustrated in Figs. 1 to 3, the sash frame consists of outer vertical and horizontal L-shaped bars 65 3 connected by T-shaped muntins 4 to form seats for the panes of glass 5. The fastener 6 is arranged in the angle between the glass 5 and the marginal flange 3^a of the sash frame, its outer face is beveled or inclined 70 to lie flush with the surface of the putty A, which is applied in the usual manner. Preferably the fastener is formed with orificed lugs 13 engaged by screws 14 which secure 75 it to the flange 3^a, although such lugs may be omitted from this form of fastener, if preferred. Centrally the fastener is formed with an external recess 8 to receive the slotted head of a bolt 9, the other threaded 80 end of which is adapted to engage a nut 10 arranged in the recess of a similar fastener member 6^a on the opposite side of the mullion 1, as shown in Fig. 2, one of the flat side faces of the nut coöperating 85 with the rear wall of the recess to prevent rotation of the nut when the bolt is turned. However, it will be understood that at the ends or corners of a partition, a shorter bolt or screw screwing directly into the adjacent frame member of the partition 90 may be used in connection with a single fastener.

In Fig. 4 I have illustrated a modified form of fastener, indicated by the numeral 11, similar in construction to that already 95 described, but in which the central recess extends as an opening or orifice 12 entirely through the fastener so that the head of the bolt 9^a seats directly on the flange 3^a of the sash frame. In this form of fastener, however, it is desirable that the orificed lugs 13 above mentioned by which the fastener is secured to the flange 3^a shall not be omitted. Where it is desired to secure two 100 sash members in place on opposite sides of a mullion, as shown, the screw-threaded end of the bolt 9^a is arranged to engage a nut disposed within the orifice of a similar fastener 11^a secured to the sash frame member 3^a of the second sash frame. 105

If desired, a solid fastener block 15, such as shown in Fig. 5 may be used in connection with a bolt and either such a fastener as shown in Fig. 2, or a fastener such as 5 that shown in Fig. 4. It is obvious, further, that this form of fastener block may be provided with lugs corresponding to the lugs 13 of the fastener shown in Fig. 3 in order to securely hold the fastener in 10 place regardless of its adhesion to the putty or the engagement of a fastening bolt.

I claim:

1. In structures of the character described and including a partition frame and a sash 15 frame having marginal outstanding flanges and a glass seated within such flanges and a beveled retaining wall of putty within the angle between the glass and flanges, a chambered fastener interposed in the putty wall 20 and extending therethrough, and a bolt having its head seated in said chambered fastener and arranged to clamp said sash frame to said partition frame.
2. In structures of the character described 25 and including a partition frame and a sash frame having marginal outstanding flanges and a glass seated within such flanges and a beveled retaining wall of putty within the angle between the glass and flanges, a chambered fastener interposed in the putty wall 30 and having a beveled top lying flush with the surface of the putty wall, and a bolt having its head seated in said chambered fastener and arranged to clamp said sash frame 35 to said partition frame.
3. In structures of the character described and including a partition frame and a sash frame having marginal outstanding flanges and a glass seated within such flanges and a beveled retaining wall of putty within the 40

angle between the glass and flanges, a chambered fastener interposed in the putty wall and having an orificed bottom adapted to engage the head of a bolt and a beveled top lying flush with the surface of the putty 45 wall, and a bolt having its head seated in said chambered fastener and arranged to clamp said sash frame to said partition frame.

4. In structures of the character described 50 and including a partition frame and a sash frame having marginal outstanding flanges and a glass seated within such flanges and a beveled retaining wall of putty within the angle between the glass and flanges, a chambered fastener interposed in the putty wall 55 and having an orificed bottom adapted to engage the head of a bolt and a beveled top lying flush with the surface of the putty wall, said fastener being formed with lugs 60 and such lugs being secured to the flange of the sash, and a bolt having its head seated in said chambered fastener and arranged to clamp said sash frame to said partition frame. 65

5. In structures of the character described, a chambered fastener according to claim 1 in which the chamber is adapted to receive the nut of the fastening bolt, whereby said fastener may be used in pairs on opposite 70 sides of an interposed mullion.

6. In structures of the character described, a pair of chambered fasteners according to claim 5 in which an interior wall of the chamber and the nut are formed to cooperate to prevent rotation of the nut and the fastener having such chamber is secured to the adjacent sash flange. 75

WILLIAM H. BURK.
